UNITED STATES PATENT OFFICE.

WALTER B. CLIFFORD, OF FRAMINGHAM, MASSACHUSETTS.

INTERNAL-COMBUSTION MOTOR.

Application filed July 2, 1925. Serial No. 41,075.

To all whom it may concern:

Be it known that I, WALTER B. CLIFFORD, a citizen of the United States, residing at Framingham, in the county of Middlesex and State of Massachusetts, have invented certain new and useful Improvements in Internal-Combustion Motors; and I do hereby declare the following to be a full, clear, and exact description of the invention, such as will enable others skilled in the art to which it appertains to make and use the same.

The present invention relates to internal combustion motors and more particularly to apparatus forming a part of this type of motor and designed for the rectification of the motor lubricant during operation.

The problem of crank case dilution in internal combustion motors has become increasingly serious in the last few years. In recognition of the gravity of the problem, a considerable number of devices have been developed and offered as solutions. All of these constructions so far as I am aware, however, are open to serious disadvantages.

In the first place, the refining operation is not carried sufficiently far to completely remove dilution. In the second place, certain of the proposed constructions, if otherwise practical, are expensive and relatively cumbersome, and in the third place, a large percentage of the heat available from the exhaust gases is wasted, lowering the efficiency of the device and reducing the capacity to such an extent that in the ordinary usage it is unequal to the demands imposed upon it and permits a progressive increase of dilution during the continued operation of the motor.

It is one object of the present invention to provide a new and improved form of oil rectifying device embodied in an internal combustion motor which shall have sufficient capacity to remove dilution from the motor lubricant substantially as it occurs.

A further object of the invention is to provide an improved form of oil rectifier which may be introduced directly into the exhaust manifold of an internal combustion motor in a manner to readily absorb the maximum heat available from the exhaust gases.

A still further object of the invention is to provide an apparatus for rectifying crank case oil which is relatively simple, inexpensive in its construction, and which may be embodied in existing types of internal com-

bustion motors without material change in the motors.

With these and other objects in view, the various features of the invention consist in certain novel features of construction, combinations and arrangements of parts herein-after described and claimed, the advantages of which will be obvious to those skilled in the art from the following description.

In the accompanying drawings illustrating the preferred form of the invention, Fig. 1 represents a side elevation of a conventional form of internal combustion motor with the improved rectifying apparatus embodied therein; Fig. 2 is a section in elevation of a portion of the exhaust manifold with the rectifying apparatus inserted therein; Fig. 3 is a detail illustrating a top plan view of a portion of the exhaust manifold and oil rectifier; and Fig. 4 is a detail illustrating a section in elevation of the upper part of a rectifier showing the vaporizing head and oil return.

The illustrated embodiment of the invention is shown in connection with an internal combustion motor having a cylinder block indicated at 10, an exhaust manifold indicated at 12, and an oil circulating pipe 14 connected with a branch pipe 16 leading into the rectifier. The oil is circulated through the pipes by a pump of the usual form (not shown). According to the present invention, the apparatus for rectifying the crank case oil is mounted directly in the exhaust manifold and subjected to the intense heat of the exhaust gases within the manifold. To this end, the apparatus comprises essentially a tubular member 20 extending vertically throughout the manifold, as indicated in Fig. 2, and having a head 22 which may project transversely of the manifold, as indicated in Fig. 3. In the embodiment of the invention shown in the drawings, the tubular member 20 and head 22 are formed as a single integral casting, thus avoiding any joints through which hot oil may pass.

The lower portion of the tubular member 20 is partially closed by a reduced neck 24 having a guide opening 25 extending therethrough. The lower edge of the guide opening 25 indicated at 26 forms a seat for a ball inlet valve 28. The ball valve 28 is normally retained in engagement with the seat 26 by a compression spring 30 inserted within a sleeve 32 provided with a thimble 34 upon which the ball rests. The

sleeve 32 is threadedly connected at its upper end with the reduced neck 24 and when the rectifier is assembled within the manifold extends downwardly below the manifold. The upper portion of the rectifier is provided with a shoulder 36 which engages with and rests upon the upper portion of the exhaust manifold and is clamped thereto by a nut 38 threaded upon the sleeve 32 and engaging with the underside of the manifold, as clearly indicated in Fig. 2. Leakage of exhaust gases is prevented by the use of washers 40 inserted on opposite sides of the manifold. This construction permits the rectifier to be assembled directly in the exhaust manifold without special machining or facing of the latter. The lower portion of the sleeve 32 is provided with a reduced end 42 which is surrounded by a swivel collar 44 retained in place by a cap nut 46. The collar 44 is provided with an annular groove 48 which is in permanent communication with a transverse passage 50 formed in the end 42. This construction insures constant communication between the passage 52 in the collar and the interior of the sleeve 32. The threaded end 54 of the collar may be connected to the oil feed line in any desired manner, as through the conventional form of union. The arrangement of the collar facilitates assembly independent of the position of the feed pipe.

The flow of oil through the tubular refining member 20 is controlled by a bellows thermostat 60 which extends lengthwise of the tubular member and is supported at its upper end by a stem 62 threaded in a head 64, which in turn is threaded in an opening in the head casting 22. The stem is retained in any adjusted position through a check nut 66. The lower end of the bellows thermostat is provided with a stem 68 projecting into the opening 25 and designed to move the ball valve 28 from the seat when a refining temperature is attained within the tubular member 20. In the usual operation, upon opening of the ball valve 28 oil is forced under pump pressure upwardly through the tubular member 20 and into the chamber 70 formed in the interior of the head 22. From the chamber 70, oil flows by gravity through the pipe 72 back to the crank case. Vapor resulting from the refining operation collects in the upper portion of the chamber 70 and passes off through the distillate pipe 76 which may discharge the vapor downwardly below the vehicle or into the air intake of the carburetor. As the bellows thermostat is completely immersed in oil at all times, it is constantly maintained at the temperature of the oil in the refining chamber and serves as an accurate gage for the control of this temperature. In actual practice, the refining temperature may be set at any desired point through a bodily adjustment of the bellows thermostat. This is accomplished by adjusting the thermostat toward or from the ball valve 28 until the stem 68 contacts with and lifts the valve at the desired temperature. In other words, if the desired refining temperature is 375° F. then a thermometer is inserted in the head 22 through the opening exposed by the removal of the cap screw 75. As the temperature within the tubular member 20 gradually rises, due to the heat of the exhaust, it is indicated on the thermometer. When the temperature as indicated by the thermometer shows that the refining point has been reached, the bellows thermostat is adjusted downwardly until the stem contacts with and opens the valve 28, admitting fresh oil to the refining chamber. This immediately reduces the temperature of the chamber and causes the valve to close. With this construction, a simple adjustment of the thermostat permits the refining temperature to be predetermined within accurate limits. It will be evident that by removing the nut 64 the thermostat may be bodily withdrawn from the rectifier without dismantling the latter. The location of the inlet valve 28 with the cooperating valve spring 34 in the tubular head depending below the exhaust manifold prevents overheating of the valve and spring, due to the intense heat of the exhaust gases. The cooling effect of the air about the tubular member is further augmented by the relatively cool oil contained within the member below the valve.

Under certain conditions stopping of the internal combustion motor may result in draining of the refining chamber of oil unless provision is made against it. This occurs if the temperature within the refining chamber is sufficient to maintain the valve open after the oil pump has stopped. If this occurs and the oil feed line is not elevated above the refining chamber it will be evident that oil will flow from the latter back into the circulation system. Thereafter when the valve closes, the refining chamber is substantially free of oil and when the motor is again started the refining operation is delayed until the valve can be opened to admit fresh oil. This delay not only introduces unnecessary lag in the refining operation but may injure the thermostat through overheating. I have found that by interposing a check valve in the oil feed line below the main valve 28 emptying of the refining chamber on stoppage of the motor may be avoided. This is simply and efficiently accomplished by locating a ball valve 80 upon a seat 82 formed inside of the sleeve 32. The ball may be guided to and from the seat by the lower end of the compression spring 30. With this construction, the ball is easily raised from its seat.

through the pump pressure but when the pump pressure is relieved immediately drops upon the seat by gravity, preventing escape of oil from the sleeve 32 and refining chamber above the sleeve. It is of great importance in an apparatus of this character that the maximum amount of heat from the exhaust may be utilized. It is furthermore desirable that the rectifying unit shall be small, compact and require a minimum of heat to raise the oil contained therein to the refining temperature. In the present construction, both of these results have been accomplished by providing a single tubular member of relatively small diameter which may be inserted directly in the exhaust manifold and which is enclosed entirely within the manifold. The tubular member and the relatively small amount of oil contained therein are quickly raised to the refining temperature with a minimum of delay and a minimum absorption of heat. Furthermore the rectifying unit, due to its unique construction, is capable of being located at the point of greatest heat in the manifold. In the illustrated embodiment of the invention showing a conventional form of exhaust manifold applied to a six cylinder motor, the rectifying unit is located directly in the manifold adjacent the point at which the manifold turns downwardly from the cylinder block and directly opposite the exhaust opening of the last cylinder in line. With this construction, the rectifying unit is subjected to the heat of the combined exhaust from five cylinders as this exhaust passes along the manifold and to the direct exhaust of one of the cylinders. As indicated clearly in Figs. 1, 2 and 3, the unit is positioned in the exhaust manifold directly opposite the exhaust port 84 of one cylinder, the gases discharged from this cylinder impinging directly upon the tubular member 20 before they have had an opportunity of becoming cooled by contact with the relatively cooler wall of the exhaust manifold. The importance of making the rectifying unit relatively small and compact and subjecting this unit to the direct action of the exhaust gases before cooling of these gases cannot be over-estimated. It will be evident to those skilled in the art that the exhaust gases give up heat rapidly and if this heat can be absorbed by the walls of the exhaust manifold or metal parts of the refining unit it is dissipated to the atmosphere without being utilized in the refining operation. Inasmuch as the refining operation is carried on at temperatures ranging from 300° F. to 400° F. or thereabouts and as the temperature of the outside air averages not more than 70° F. it is evident that the transfer of heat from the exhaust gases to the air will be much more rapid than the transfer of heat from the exhaust gases to the rectifying unit unless provision is made to counteract this effect. In the present construction, the heat available from the exhaust is utilized so successfully that the oil within the rectifying unit is actually raised to refining temperature substantially before the walls of the exhaust manifold have reached this temperature. In other words, the rectifying unit, owing to its location and construction, robs the manifold of heat from the exhaust gases. In order to expedite the transfer of heat from the exhaust gases to the oil within the rectifying unit, the tubular member is preferably made of copper, brass or similar material which offers a suitable medium for the passage of heat therethrough. In order to avoid creating a back pressure within the exhaust manifold at the location of the rectifying unit, the manifold, as indicated clearly in Figs. 2 and 3, is bulged in two directions, creating an enlarged space 90 opposite the exhaust port 84. This enlarged space affords ample passage for exhaust gases about the rectifying unit and does not interfere with the flow of these gases. A further advantage of locating the rectifying unit directly in the exhaust manifold is due to the fact that the unit is insulated from the outside air by the hot exhaust gases and is accordingly substantially free in its operation from the influence of outside temperatures. In constructions in which it is attempted to bypass a portion of the exhaust, on the other hand, about a rectifying chamber, radiation of heat through the outer walls to the rectifying unit is sufficiently great, especially at low temperatures, to practically nullify the advantages of the rectifier. Inasmuch as the greatest dilution normally occurs during cold weather, the disadvantage of this form of construction will be apparent.

In ordinary practice it has been found that satisfactory results are obtained if rectification of the oil is carried out at temperatures ranging from 300° F. to 350° F. As will be evident from an inspection of the drawings, the oil passing upwardly through the tubular portion 20 of the unit is heated to the predetermined refining temperature. At these temperatures substantially all of the liquid diluents in the oil are caused to vaporize. A large percentage of this vaporized diluent passes from the oil in the chamber 70 which has an upwardly inclined wall to provide a gradually increasing vapor space having its greatest volume where connected to the distillate pipe 76. The hot oil travels in a relatively thin sheet along the bottom wall of the chamber 70 and is discharged into the return pipe 72. It will be evident that the oil passes through the rectifying unit in a comparatively small stream which is insufficient to fill the return pipe 72. The hot oil flowing down

this pipe is ordinarily subjected to a current of air flowing upwardly through the pipe and induced by the outward draft through the distillate pipe 76. This upward draft may be created independently of whether the return pipe 72 is connected directly into the crank case above the oil level or into the filler pipe as indicated in Fig. 1. The flow of air upwardly through this return pipe of extra large capacity serves to remove a considerable percentage of vapors which otherwise might be entrained with the descending stream of oil and return to the crank case. It is believed that the provision of such a return pipe leading from the rectifying unit and designed to permit a flow of air counter to the returning oil stream is a material factor in insuring more or less complete removal of the previously vaporized diluents.

1. An internal combustion motor comprising an exhaust manifold having a passage, a tubular member extending across the passage in the manifold and subjected to the direct action of exhaust gases passing therethrough, means for delivering oil to the member, means governed by the temperature of the oil within the member for regulating the admission of oil to the member, and means for discharging heated oil and vapor from the member.

2. An internal combustion motor comprising an exhaust passage, a tubular oil rectifier of relatively small diameter extending through the passage and subjected to the direct action of exhaust gases in the passage, a thermostat positioned in the tubular rectifier and extending lengthwise thereof, an oil admission valve located adjacent one end of the rectifier and opened by the thermostat when a predetermined refining temperature of oil in the tubular rectifier is reached, a vaporizing chamber communicating with the end of the tubular rectifier opposite the valve, and means for permitting the withdrawal of hot oil and vapor from the chamber.

3. An internal combustion motor comprising an exhaust manifold, a tubular member mounted within the manifold and having its upper and lower ends projecting beyond the manifold, the intermediate portions of the member being completely enclosed within the manifold, means for delivering oil to the lower projecting end of the member, means governed by the temperature of oil within the member for regulating the admission of oil to the member, and means for permitting the withdrawal of hot oil and vapor from the upper portion of the member.

4. An internal combustion motor comprising an exhaust manifold, an oil tube of comparatively small diameter extending through the manifold and subjected to the

direct action of exhaust gases, a bellows thermostat enclosed within the tube and extending lengthwise thereof, an oil admission valve located in one end of the member and controlled by the thermostat, and means for withdrawing oil and vapor from the opposite end of the member.

5. An internal combustion motor comprising an exhaust manifold, an oil tube projecting through the manifold in an upright position, a thermostat positioned inside of the tube and extending lengthwise thereof, an oil admission valve located in the lower end of the tube below the manifold and controlled by the thermostat, and means for separately withdrawing heated oil and vapor from the upper end of the tube above the thermostat.

6. An internal combustion motor comprising an exhaust manifold, an oil tube projecting through the manifold in an upright position, a thermostat positioned inside of the tube and extending lengthwise thereof, an oil admission valve located in the lower end of the tube and controlled by the thermostat, a vaporizing chamber connected to the upper portion of the tube, means for draining hot oil from the chamber, and means for permitting the withdrawal of vapor therefrom.

7. An internal combustion motor comprising an exhaust manifold, an oil tube projecting through the manifold, a thermostat positioned inside of the tube and extending lengthwise thereof, an oil admission valve located in the lower end of the tube and controlled by the thermostat, a vaporizing chamber communicating with the upper end of the tube, an oil return pipe of excessive capacity for draining the chamber, connections for permitting an upward flow of air through the return pipe, and means communicating with the chamber for permitting the withdrawal of vapor.

8. An internal combustion motor comprising an exhaust manifold, an oil tube projecting through the manifold in an upright position, a thermostat positioned inside of the tube and extending lengthwise thereof, an oil admission valve located in the lower end of the tube and controlled by the thermostat, a vaporizing head mounted on the upper end of the tube and in free communication therewith, means for adjustably supporting the thermostat from the vaporizing head, means for draining hot oil from the vaporizing head, and means for permitting the withdrawal of vapor therefrom.

9. An internal combustion motor comprising an exhaust manifold, an oil tube projecting through the manifold in an upright position, a thermostat positioned inside of the tube and extending lengthwise thereof, an oil admission valve located in the lower end of the tube and opened by the thermo-

- stat when a predetermined refining temperature of the oil is reached, means for delivering oil under pressure to the admission valve, and means for separately withdrawing heated oil and vapor from the upper end of the tube.
10. An internal combustion motor comprising a rectifying chamber adapted to contain oil, means for heating the chamber, a thermostat immersed in oil in the chamber, an oil admission valve in the lower end of the chamber controlled by the thermostat, means for delivering oil under pressure to the valve, and separate means for preventing drainage of oil from the chamber if the pressure ceases.
11. An internal combustion motor comprising an upright tube of comparatively small diameter, an exhaust manifold through which the tube passes, means for clamping the tube within the manifold at opposite sides of the manifold, an elongated bellows thermostat supported within the tube and extending lengthwise thereof, means for adjustably supporting the thermostat at one end, an oil admission valve at the opposite end controlled by the thermostat, means for delivering oil under pressure to the valve, and means for separately withdrawing hot oil and vapor from the opposite end of the tube.
12. An internal combustion motor comprising a tubular oil rectifier of comparatively small cross section, an exhaust manifold within which the rectifier is mounted in an upright position, the manifold completely surrounding the rectifier, a bellows thermostat enclosed within the rectifier, an oil admission valve controlled by the thermostat, and means for causing the thermostat to be completely immersed in oil within the rectifier.
13. An internal combustion motor comprising an exhaust port, a tubular rectifier unit positioned directly in the path of gases emerging from the port, a bellows thermostat enclosed within the rectifier, means for admitting oil to the rectifier controlled by the thermostat, and means for maintaining the thermostat completely immersed in oil within the rectifier.
14. An internal combustion motor comprising a rectifier tube, a vaporizing head formed integrally with the upper end of the tube, an oil admission passage in the lower end of the tube, a separate head detachably connected to the lower end of the tube, a valve supported by the second head, an elongated thermostat adjustably supported from the vaporizing head and adapted to control the operation of the valve, and means for delivering oil under pressure to the interior of the second head below the valve.
15. An internal combustion motor comprising an exhaust manifold, an oil rectifier tube extending vertically therethrough, a vaporizing head formed integrally with the upper end of the tube and projecting transversely of the manifold, means controlled by the temperature of the oil within the tube for regulating the flow of oil therethrough, an oil return pipe connected to the bottom of the vaporizing head adjacent its outer end, and a vapor passage communicating with the upper portion of the head in proximity to the oil return pipe.

In testimony whereof I have signed my name to this specification.

WALTER B. CLIFFORD.
